Fig. 4**Fig. 5****Fig. 6****Fig. 7****Fig. 8****Fig. 9****Fig. 10**

FIG. 1 is an elevational view of a jug showing my new design, the opposite side being a mirror image of the side shown;

FIG. 2 is an elevational view thereof, looking from the left of FIG. 1;

FIG. 3 is an elevational view thereof, looking from the right of FIG. 1;

FIG. 4 is a bottom plan view thereof; and

FIGS. 5 to 10, inclusive, are cross-sectional views thereof taken on the lines 5—5, 6—6, 7—7, 8—8, 9—9, and 10—10 of FIG. 1, respectively, to show the wall configuration at those sections.

I claim:

The ornamental design for a jug, as shown and described.
